**HINGED CONDUCTING MEANS FOR
DISCONNECTING SWITCH**

Chester W. Upton, Jr., Trafford, Pa., assignor to Westinghouse Electric Corporation, Pittsburgh, Pa., a corporation of Pennsylvania

Filed Oct. 21, 1966, Ser. No. 588,530
4 Claims. (Cl. 200—48)

ABSTRACT OF THE DISCLOSURE

A high voltage disconnect switch in which the hinge member pivotally supporting the switch blade has a central tubular portion inside of which a generally C-shaped, resilient conducting member is disposed; the C-shaped member being between and engaging both a portion of the connecting link and the hinge member to maintain a conducting path between the switch frame and the blade when the blade is disengaged from the stationary contacts.

This invention relates to disconnecting switches and more particularly to hinged conducting structures which form part of such switches.

In the construction of certain known types of disconnecting switches, such as disclosed in U.S. Patent 2,527,924, issued Oct. 31, 1950, to Fjellstedt et al., a movable switch blade is actuated to engage and disengage a pair of associated spaced main stationary contacts or break jaws at the opposite ends of the switch blade during the closing and opening of the switch. Since such switches are frequently required to interrupt different magnitudes of charging or magnetizing currents during the opening of the switch, which may involve the use of arcing horns at the free end of the switch blade to protect the main contacts and the contact area on the switch blade, it has been found necessary to provide a bridging conducting member at the hinged end of the switch blade in order to maintain an electrically conducting path from the switch blade to the supporting hinge structure to thereby prevent arcing and burning or pitting of the main stationary contacts of the switch at the hinged end of the switch blade when the hinged end of the switch blade is disengaged from the latter contacts during the opening of the switch. One type of bridging conducting member which has been employed for this purpose comprises a conducting leaf spring which extends from a stationary support at the hinged end of the switch blade to bear against the external surfaces of the switch parts which are secured to the hinged end of the switch blade. It has been found that this type of bridging conducting arrangement is subject to operating problems or malfunctions particularly in icy weather conditions or in corrosive atmospheric conditions since the contact pressure provided by the leaf spring may be reduced or inadequate to clean the associated contact surfaces and to maintain an adequate conducting path during long periods of exposure to such atmospheric conditions. It is therefore desirable to provide an improved disconnecting switch structure of the type described including improved hinged conducting means.

It is an object of this invention to provide a new and improved disconnecting switch structure.

Another object of this invention is to provide an improved hinged conducting means for disconnecting switches.

A more specific object of this invention is to provide an improved means for maintaining a conductive path between the movable blade of a disconnecting switch and its associated hinge support when the blade is disengaged from both of the associated main stationary contacts during opening.

Other objects of the invention will, in part, be obvious and will, in part, appear hereinafter.

For a fuller understanding of the nature and objects of the invention, reference should be had to the following 5 detailed description, taken in conjunction with the accompanying drawings, in which:

FIGURE 1 is a side elevational view of a disconnecting switch structure embodying the principal features of the invention;

FIG. 2 is a top plan view of the disconnecting switch shown in FIG. 1;

FIG. 3 is a view, partly in side elevation and partly in section, of a portion of the disconnecting switch shown in FIG. 1;

FIG. 4 is a view, partly in end elevation and partly in section, taken along the line IV—IV in FIG. 3;

FIG. 5 is a view, in side elevation, of a portion of the disconnecting switch shown in FIG. 1 and illustrating the position of certain parts during the opening movement of 20 the switch blade which forms part of the switch; and

FIG. 6 is a sectional view of a portion of the structure shown in FIG. 3, taken along the line VI—VI in FIG. 3.

Referring now to the drawings and FIGS. 1 and 2 in particular, there is shown a disconnecting switch assembly 25 10 which comprises three spaced insulator stacks 32, 34 and 36 mounted upon a common base support 44. The base 44 is preferably a metal channel having flanges which extend outwardly from the sides of the channel. Each of the insulator stacks 32, 34 and 36 comprises a plurality of insulators which are preferably formed from porcelain or a similar material. The number of insulators required in each of the insulator stacks 32, 34 and 36 depends upon the voltage of the system in which the disconnecting switch 10 is applied. The insulator stacks 32 and 34 are 30 mounted upon the fixed pedestals or spacers 33 and 37, respectively, which may be secured to the top of the base 44. The insulator stack 34 is mounted upon a shaft 61, the lower end of which is rotatably mounted in a bearing 63 which is secured to the base 44. An operating lever or 35 crank arm 62 may be secured to the shaft 61 to rotate the insulator stack 34 during the operation of the disconnecting switch 10, as will be explained hereinafter.

The disconnecting switch 10 includes a first generally U-shaped main stationary contact assembly or break jaw assembly 20 which is mounted on and secured to the top 40 of the insulator stack 32, as shown in FIGS. 1 and 2. The stationary contact assembly 20 includes a pair of spaced contact jaws 48 which are interconnected by a base portion or bight portion that is secured to the top of the insulator stack 32 by suitable means, such as bolts. A terminal pad 46 which is adapted to receive a terminal connector is also secured to the top of the insulator stack 32 and includes a vertical extension 46A which may be 45 formed integrally therewith and which acts as a stop for the movement of the associated switch blade 42 into engagement with the contact jaws 48. In addition, a stationary arcing horn 49 may also be secured to the top of the insulator stack 32 as shown in FIGS. 1 and 2.

The contact jaws 48 are of the reverse loop type which 50 have the characteristic of magnetically forcing the associated switch blade 42 downwardly between the break jaws in a direction toward the base portion which interconnects the contact jaws and against the blade stop 46A when a relatively high momentary current flows through 55 the disconnecting switch 10. The contact jaws 48 are 60 preferably formed from a suitable material which combines relatively high electrical conductivity with excellent spring characteristics, such as zirconium copper or cadmium chrome copper. The resilient nature of the contact jaws 48 substantially eliminates the need for 65 additional spring or biasing means to bias the contact 70

jaws 48 toward one another for gripping the free end of the associated switch blade 42 when the switch blade 42 is actuated to engage the contact jaws 43.

The disconnecting switch 10 also includes a second main stationary contact assembly 30 which is mounted on a generally U-shaped stationary support frame 80 which in turn is mounted on top of and secured to the insulator stack 36 and is formed or cast from a suitable material which combines relatively high electrical conductivity with sufficient structural strength, such as an aluminum bronze alloy. The support frame 80, as illustrated, includes a terminal pad 86 which may be formed integrally therewith and which is adapted to receive a terminal connector. The second main stationary contact assembly or main hinge contact assembly 30 includes a pair of spaced contact jaws 92 which are interconnected by a base portion or bight portion which is secured to a central shoulder or bracket portion of the support frame 80, as indicated at 83, by suitable means, such as bolts. Similarly to the contact jaws 48, the contact jaws 92 are preferably formed from a suitable material which combines relatively high electrical conductivity with excellent spring or resilient characteristics, such as the materials previously mentioned, to eliminate the need for additional spring means or biasing means to bias the contact jaws 92 toward one another to provide sufficient contact pressure with the adjacent end of the associated switch blade 42 when the switch blade 42 engages the contact jaws 92.

In order to electrically bridge the spaced main stationary contact assemblies 20 and 30 just described when the disconnecting switch 10 is in the closed position shown in FIGS. 1 and 2, the movable switch blade 42 is disposed to engage both of the stationary contact assemblies 20 and 30 along an axis which extends between the contact assemblies 20 and 30 when the switch 10 is in the closed circuit condition shown in FIGS. 1 and 2. As illustrated, the switch blade 42 is generally tubular in configuration with the opposite ends being generally rectangular in cross-section to provide high pressure contact areas which engage the associated contact jaws 48 and 92 of the contact assemblies 20 and 30, respectively. In order to facilitate the interruption of magnetizing or charging currents during the opening of the switch 10, a movable arcing horn 47 may be mounted at the free end of the blade 42 to cooperate with the stationary arcing horn 49 during such an opening operation.

In order to support the switch blade 42 for rotation about its own axis and for arcuate movement about an axis which extends generally transversely with respect to the axis of the switch blade 42, the spaced arms 82 of the support frame 80 are disposed on opposite sides of the right end of the switch blade 42, as viewed in FIGS. 1 and 2. The hinge member 72 is pivotally supported between the arms 82 of the support frame 80 by the bolts 84 which pass through aligned openings in the arms 82 and the hinge member 72, as best shown in FIG. 2, with the right end of the switch blade 42 being disposed to pass through the central tubular portion of the hinge member 72 to engage the associated contact assembly 30 when the disconnecting switch 10 is in the closed position shown in FIGS. 1 and 2. It is to be noted that the hinge member 72 is rotatable about an axis which extends through the bolts 84, as viewed in FIG. 2, and which intersects the axis of the switch blade 42 at substantially a right angle.

In order to actuate the switch blade 42 between open and closed positions with respect to the associated contact assemblies 20 and 30, the connecting link member 90 is secured to the switch blade 42 for movement therewith. In particular, the connecting link 90 includes a first portion 138 which is secured to the switch blade 42 by suitable means, such as the bolt 85, which passes through aligned openings in the first portion 138 of the connecting link 90 and the switch blade 42. The first

portion 138 of the connecting link 90 which is generally tubular in configuration includes a portion indicated at 138A which is concentrically disposed between the hinge member 72 and the switch blade 42 and which projects axially along the switch blade 42 to the right of the hinge member 72, as viewed in FIG. 3. In order to rotatably support the switch blade 42, along with the first portion 138 of the connecting link 90, in the central portion of the hinge member 72, the flanged sleeve bearing members 142 and 144 are disposed between the first portion 138 of the connecting link 90 and the hinge member 72 as best shown in FIG. 3. The flanged sleeve bearing members 142 and 144 are axially spaced from one another along the switch blade 42 and are formed from a suitable material, such as bronze, which is coated with a material having a relatively low coefficient of friction, such as the material polytetrafluoroethylene which is sold under the trademark "Teflon." The bearing members 142 and 144 are maintained in assembled relationship with the associated hinge member 72 and the connecting link 90 by the flange portion 136 which is provided on the first portion 138 of the connecting link 90 and the retaining ring 152, which is disposed in a groove provided adjacent to the end of the portion 138A of the connecting link 90 on the other side of the hinge member. The connecting link 90 is also provided with an arm portion 132 which is tubular in configuration and which projects from the first portion 138 of the connecting link 90 at an angle of substantially 45 degrees with respect to the longitudinal axis of the switch blade 42. The axis of the arm portion 132 of the connecting link 90 also intersects the axis of rotation of the switch blade 42 which extends between the bolts 84 as previously described.

In order to actuate the arm portion 132 of the connecting link 90 and, in turn, the switch blade 42, the crank member 52 is mounted on top of and secured to the insulator stack 34 by suitable means, such as bolts. The crank member 52 includes a base portion 52A and a bearing portion 52B which is adapted to receive the arm portion 132 of the connecting link 90. In order to rotatably support the connecting link 90 in the bearing portion 52B of the crank member 52, a pair of flanged sleeve bearing members 122 and 124 are disposed at the opposite ends of the bearing portion 52B of the crank member 52 between the arm portion 132 of the connecting link 90 and the inner surface of the bearing portion 52B of the crank member 52. In order to maintain the bearing members 122 and 124 in assembled relationship with the associated arm portion 132 of the connecting link 90 and the bearing portion 52B of the crank member 52, the flange portion 134 is provided on the connecting link 90 and a retaining ring 126 is disposed on the lower end of the arm portion 132 of the connecting link 90 in a groove provided adjacent to the lower end of the arm portion 132. It is to be noted that the crank member 52 is rotatable with the insulator stack 34 about an axis which substantially intersects the longitudinal axis of the switch blade 42, the axis of rotation of the hinge member 72, and the axis of rotation of the arm portion 132 of the connecting link 90, which intersects the longitudinal axis of the switch blade 42 at an angle of substantially 45 degrees and which also intersects the axis of rotation of the crank member 52 at an angle of substantially 45 degrees, as best shown in FIG. 3.

In order to limit the arcuate travel or movement of the switch blade 42 from the closed position shown in FIG. 1 to the open position which is angularly displaced from the closed position shown in FIG. 1 by an angle of substantially 90 degrees about the axis of rotation of the hinge member 72, the stop member 53 is mounted on the base portion 52A of the crank member 52 and may be formed integrally therewith to engage the lower end of the switch blade 42, as best shown in FIG. 5, when the switch blade 42 is actuated to the open position.

In order to assist the actuation of the switch blade 42 from the open position which is angularly displaced from the closed position shown in FIG. 1 by substantially 90 degrees as just mentioned, when the mechanical advantage of the hinge conducting structure just described is substantially at a minimum, the cam member or projecting portion 52C, as shown in FIG. 6, is mounted on or formed integrally with the bearing portion 52B of the crank member 52 and is disposed to engage one end of an arm 72A which extends from a flange portion 72B on the hinge member 72 toward the contact assembly 30 and the contact jaws 92, as shown in FIG. 3. More specifically, when the switch 10 is actuated from the open position, in which the blade 42 is disposed generally vertically, as viewed in FIG. 5, the cam portion 52C on the crank member 52 engages the arm 72A on the hinge member 72 from about 10° to 20° of the rotation of the insulator stack 34 during the initial rotation of the insulator stack 34 toward the closed position to transmit a driving torque to the switch blade 42 directly from the crank member 52 to the hinge member 72 and the switch blade 42.

In order to maintain a conducting path between the switch blade 42 and the conducting frame support 80 during the opening movement of the switch blade 42, a generally C-shaped conducting member 112 is disposed generally concentrically between the hinge member 72 and the first portion 138A of the connecting link 90, as best shown in FIGS. 3 and 4, to engage both the inner surface of the central portion of the hinge member 72 and the outer surface of the portion 138A of the connecting link 90 at a plurality of points, as shown in FIG. 4, to prevent any burning or arcing at the hinged conducting structure of the disconnecting switch 10 previously described. The conducting member 112 is preferably formed from a material which combines relatively high electrical conductivity with excellent spring or resilient characteristics such as phosphorus bronze or a zirconium copper alloy. Because of the resilient or spring characteristic of the material from which the conducting member 112 is formed, different points or portions of the conducting member 112 are biased into engagement with both the hinge member 72 and the connecting link 90 and more specifically bears against the central portion of the hinge member 72 and the outer surface of the first portion 138A of the connecting link 90. It is to be noted that the conducting member 112 is disposed axially between the bearing members 142 and 144, as best shown in FIG. 3. It is also important to note that the conducting member 112 is disposed internally inside the hinge member 72 and is protected by the bearing members 142 and 144 as well as by the first portion 138A of the connecting link 90 to prevent the formation of ice or the adverse effect of corrosive atmospheres which might otherwise affect the performance of the conducting member 112 or the conducting path which is provided by the conducting member 112 during long service of the disconnecting switch 10.

In the overall operation of the disconnecting switch 10, when the insulator stack 34 is rotated by an external operating mechanism (not shown) through the crank member or operating lever 62, from the position shown in FIGS. 1 and 2, the switch blade 42 is first actuated through the crank member 52, and the connecting link 90, as guided by the hinge member 72, to rotate about its own longitudinal axis until the contact pressure between the contact surfaces provided at the free end of the switch blade 42 as indicated at 42A is reduced. Simultaneously or subsequently, the switch blade 42 is rotated in an arcuate path about the axis which extends through the bolts 84 from the closed position indicated in FIGS. 1 and 2 to the open position which is displaced from the closed position by an angle of substantially 90 degrees in a clockwise direction, as viewed in FIG. 1. During the opening movement of the switch blade from the closed position shown in FIG. 1, both ends of the switch blade will be disengaged from the associated contact assem-

blies 20 and 30 and after the right end of the switch blade 42 as viewed in FIGS. 1 and 2 is disengaged from the contact assembly 30, the conducting member 112 maintains an electrically conducting path from the switch blade 42 to the electrically conducting support 80 which extends from the switch blade 42, through the connecting link 90, which is also formed from an electrically conducting material, the conducting member 112, the electrically conducting hinge member 72, the electrically conducting bolts 84 and the contact areas provided on the arm portions 192 of the hinge member 72, which are generally circular in configuration, as best shown in FIGS. 2 and 3. The latter conducting path is very important in preventing arcing or pitting or burning of the hinge conducting structure provided as part of the disconnecting switch 10 when the disconnecting switch 10 is required to interrupt charging or magnetizing currents in a particular application which would otherwise cause such arcing or pitting in a disconnecting switch contact. As previously mentioned, the stop member 53 provided on the base portion 52A of the crank member 52 limits the arcuate travel of the switch blade 42 from the closed position shown in FIGS. 1 and 2 to the open position which is angularly displaced from the closed position by an angle of substantially 90 degrees, as best shown in FIG. 5 where the switch blade 42 is shown approaching its ultimate open position.

In the closing operation of the disconnecting switch 10, the insulator stack 34 is rotated through the crank member 52 or operating lever 62 from the position indicated in phantom at 62' in FIG. 2 to the position indicated in solid in FIG. 2 to thereby actuate the switch blade 42 from the open position through the crank member 52 and the connecting link 90, as guided by the hinge member 72, to the closed position shown in FIGS. 1 and 2. As previously mentioned, during the initial rotation of the insulator stack 34 from the position which corresponds to the position of the operating lever indicated at 62' in FIG. 2, the arm 72A provided on the hinge member 72 is engaged by the cam surface 52C on the bearing portion 52B of the crank member 52, as best shown in FIG. 6, to actuate the switch blade 42 initially from the open position when the mechanical advantage of the drive system which includes the insulator stack 34 and the crank member 52 as well as the connecting link 90 and the hinge member 72 is substantially at a minimum to insure proper operation of the disconnecting switch 10 during closing of the disconnecting switch. It has been found that the driving torque or forces exerted on a switch blade 42 through the cam member 52C and the arm 72A of the hinge member 72 are effective during a closing operation of the switch blade 42 from about 10 degrees to 20 degrees of the initial rotation of the insulator stack 34 from the position which corresponds to the position of the operating lever, as indicated at 62' in FIG. 2, toward the position of the insulator stack 34 which corresponds to the position of the operating lever 62 as shown in solid lines in FIG. 2. It is to be noted that during the final movement of the switch blade 42 to the closed position shown in FIG. 1, the blade 42 is rotated about its own axis to insure adequate contact pressure between the contact surfaces at each end of the blade and the associated contact jaws 48 and 92.

It is to be understood that in certain applications the disconnecting switch structure shown may be modified to provide a conducting path directly between the switch blade 42 and the electrically conducting hinge member 72 by enlarging the outer diameter of the switch blade 42 as best indicated in FIG. 3 and omitting the portion of the connecting link 90, as indicated at 138A, which extends from the flange portion 136 to the retaining ring 152 with the bearing members 142 and 144 being then disposed between the inner surface of the central portion of the hinge member 72 and the outer surface of the enlarged switch blade 42 as thus modified. In such a modified arrangement, the bearing members 142 and 144 may be main-

tained in assembled relationship with the associated hinge member 72 and the switch blade 42, as thus modified, by the flange portion 136 of the modified connecting link 90 and a retaining ring similar to the retaining ring 152 which would be disposed in a suitable groove provided in the enlarged portion of the switch blade 42 as modified.

It is important to note that the conducting path maintained by the conducting member 112 in a construction as disclosed is only effective or required during the portion of the arcuate travel of the switch blade 42 in an opening operation after the opposite ends of the switch blade 42 which provide the high pressure contact areas have both been disengaged from the associated main stationary contact assemblies 20 and 30, respectively, to prevent the arcing or pitting or burning of the hinged conducting structure of the disconnecting switch 10 that would otherwise result and that the conductive path provided by the connecting member 112 is therefore only required to conduct substantial current during a portion of the opening travel of the switch blade 42. The normal current path through the disconnecting switch 10 when the switch blade 42 is in the closed position shown in FIGS. 1 and 2 extends from the terminal pad at the left end of the switch 10, through the contact jaws 48, the contact portion 42A of the switch blade 42, the main body of the switch blade 42, the contact jaws 92 of the stationary contact assembly 30 to the electrically conducting frame support 80 and finally to the terminal pad 86 at the right end of the disconnecting switch 10 as viewed in FIGS. 1 and 2. The normal conducting path through the switch 10 is designed to have a relatively lower resistance than the conducting path which includes the conducting member 112.

The apparatus embodying the teachings of this invention has several advantages. For example, in a disconnecting switch of the type described in which the opposite ends of the switch blade are actuated to be disengaged from both of the main stationary contact assemblies as described, a conducting path is maintained from the switch blade through the associated hinged conducting structure previously described by the conducting member 112 and the associated conducting parts which prevents arcing or burning or pitting of the different parts which make up the hinged conducting structure of the switch 10. The conducting path which is maintained during a portion of the opening travel of the switch blade in a switch structure as described is completely protected from adverse weather conditions, such as ice and snow and from corrosive atmospheric conditions, which might otherwise reduce the contact pressures or the resilience of the conducting member 112 during long periods of service of the disconnecting switch 10.

Since numerous changes may be made in the above described apparatus and different embodiments of the invention may be made without departing from the spirit and scope thereof, it is intended that all matter contained in the foregoing description or shown in the accompanying drawings shall be interpreted as illustrative and not in a limiting sense.

What is claimed is:

1. A disconnecting switch comprising a pair of stationary contact members disposed in spaced relation along a first axis, a switch blade disposed generally along the first axis to engage both of the stationary contact members when the switch is in the closed position, a conducting stationary frame disposed adjacent to one end of the blade and having one of the stationary contact members mounted thereon, a conducting hinge member having a central tubular portion pivotally supported on the frame for rotation about a second axis which intersects

the first axis at substantially a right angle, said one end of the blade being disposed to pass through and being radially spaced from the central tubular portion of the hinge member, a connecting link secured to the blade 5 adjacent to said one end and having a first portion rotatably supported between the blade and the hinge member and an arm projecting at an angle of substantially 45° with respect to the first axis, a crank member rotatable about a third axis which substantially intersects said first and second axes and having a bearing portion adapted to rotatably receive the arm of the connecting link, and a generally C-shaped, resilient conducting member disposed inside the central tubular portion of said hinge member between and engaging both the first portion of the connecting link and the hinge member to maintain a conducting path between the frame and the blade which extends through the generally C-shaped conducting member and the first portion of the connecting link when the crank member is rotated to actuate the blade to a disengaged position with respect to both of the stationary contact members.

2. The combination as claimed in claim 1 wherein a pair of flanged sleeve bearing members are rotatably disposed between the hinge member and the first portion 10 of the connecting link on the opposite sides of the generally C-shaped conducting member.

3. The combination as claimed in claim 1 wherein both of the stationary contact members are generally U-shaped in configuration with the opposite ends of the 15 blades which engage the stationary contact members being generally rectangular in cross-section.

4. A disconnecting switch comprising a pair of stationary contact members disposed in spaced relation along a first axis, a switch blade disposed generally along the 20 first axis to engage both of the stationary contact members when the switch is in the closed position, a conducting stationary frame disposed adjacent to one end of the blade and having one of the stationary contact members mounted thereon, a conducting hinge member 25 having a central tubular portion pivotally supported on the frame for rotation about a second axis which is generally transverse to the first axis, said one end of the blade being disposed to pass through and being radially spaced from the tubular portion of the hinge member, a connecting link having a first portion secured 30 to said blade adjacent to said one end for movement with the blade and an arm projecting at an angle of substantially 45° with respect to the first axis, a crank member rotatable about a third axis which substantially intersects said first and second axes and having a bearing portion 35 adapted to rotatably receive the arm of the connecting link, and a generally C-shaped, resilient conducting member disposed inside the central tubular portion of said hinge member between and directly engaging both the hinge member and the blade to maintain a 40 conducting path between the frame and the blade which extends through the last-mentioned conducting member and the hinge member when the crank member is rotated to actuate the blade to a disengaged position with respect to both of the stationary contact members.
